INSULATED DISCHARGE TUBE TERMINAL

Filed March 21, 1931

INVENTOR

Fred Hotchner

UNITED STATES PATENT OFFICE

FRED HOTCHNER, OF LOS ANGELES, CALIFORNIA

INSULATED DISCHARGE TUBE TERMINAL

Application filed March 21, 1931. Serial No. 524,270.

This invention provides an insulated discharge tube terminal and relates to an internal insulating element or assembly for a discharge tube such as in illuminating tube 5 for use on electric signs at the places where such tubes pass thru the metal of the sign face to make connection with the current supply wires.

The greatest source of service troubles with 10 discharge tube signs at the present time is breakdown at the terminals. External insulating devices have proven inadequate, even when made quite bulky, to meet the entire range of conditions common in practice. The present invention overcomes the 15 various objections to external insulators, reduces the size of holes necessary in the body of the sign to pass the tubes, eliminates any protruding terminal element other than the 20 tube itself, and provide effective insulation under all weather conditions.

In a previously filed application of mine, Serial No. 495,648, dated November 14, 1930, I have disclosed an internal insulator in 25 which an exceedingly thin layer of gas adjacent the wall of the tube was made to serve as an insulator, the layer of gas being in contact with a conductor. I have found that there is a restrictive effect that may be utilized 30 in a thin layer of gas bounded by a dielectric. One object of the invention, therefore, is to provide an insulated terminal in which the restrictive effect of an exceedingly thin layer of gas is utilized to resist 35 break-down.

Another object of the invention is to provide an insulating body instead of a conducting body as the main element of the assembly.

A further object is to provide an insulated 40 terminal which may be readily fabricated and that does not require unusual care in making with sufficient accuracy to insure commercially uniform quality.

A further object of one of the forms of 45 the invention is to increase the resistance to a possible break-down discharge by a packing of discharge stopping material which also serves to position the main insulating element in the tube.

50 A further object of one of the forms of

the invention is to increase to a very great extent the length of a possible flash-thru discharge by making the passage thru the layer of gas take the form of a helix on considerable length. 55

Other objects of the invention will be apparent from the accompanying drawing and the following specification, in which two embodiments of the invention are set forth. It is to be understood that the invention is not 60 limited to the particular embodiments shown but may be variously applied in the construction of discharge tube devices and is to be limited only by the prior art and the appended claims. 65

Figure 1 is a view in section of a tube terminal made according to this invention.

Figure 2 is a perspective view of the main insulating element of the terminal shown in 70 Figure 1.

Figure 3 is a sectional view of another embodiment of the invention.

Figure 4 is a perspective view of the main insulating element of the terminal shown in 75 Figure 3.

Numeral 1, Figure 1 indicates a discharge tube such as an illuminating tube which is mounted on a supporting body such as a sign body, numeral 6 indicating a portion of such a body to which a break down discharge 80 might occur at the place where the tube terminal passes thru the body to make connection with the current supply wires. The section of the tube which is insulated by the features of this invention against such break 85 down is indicated by numeral 5.

Numeral 2 indicates the electrode end of the terminal. The electrode proper is indicated by 3, and the lead in conductor, to which connection is made from the supply wires, by 4. The tube is supported from the sign body by a plurality of insulating posts such as the post indicated by 7. 90

The section of the tube indicated by 5 is 95 somewhat larger in diameter than the remainder there being two shoulders 16 and 17 between which the insulating bushing 3 is positioned. Between these shoulders and the shoulders 18 and 19 of the bushing 3 are 100 placed packing rings of discharge stopping

material indicated by 9 and 10. A suitable material for this packing is glass wool, but various other materials may be used. In some cases a metallic packing serves because of the great resistance offered to a discharge by small bodies of gas. This packing also serves as a mechanical support for the bushing and compensates for irregularities in the fabrication of the device as well as serving as a cushion for the bushing. The diameter of the bushing is slightly less than the inside diameter of the section of the tubing in which it is positioned, there being a very thin layer of gas indicated by 11, thru which a discharge can not pass under normal conditions, remaining between the bushing and the tube. If this layer of gas is sufficiently thin the resistance is very great and in conjunction with the bushing 8 forms an effective insulator.

While there is a generally accepted theory of the reason for the high resistance of a thin layer of gas in contact with a conducting body the exact condition of a thin layer of gas bounded by dielectric material is a matter of speculation. The invention is not to be limited by any theory, the opinion here given being in the way of assisting one practicing the invention in comprehending the device and selecting appropriate materials for the same.

It is known that when conditions exist in a body of gas such that an electron collides with few or no atoms that conduction can not take place. Given a thin layer of gas and a conducting body in contact with an appreciable boundary of the gas body, once we know the electrical condition of the conducting body we can judge the probability of electron movement and predict the behavior of the device. Given a thin body of gas bounded by dielectric material we are confronted with the problem of charges on the surface of the dielectric material and the rate of change of the charges, an altogether baffling subject and one which is still in the state of the art shrouded with much obscurity. It is my belief that the reason for the operation of the device is that material ionization does not occur in the gas layer by diffusion from the ionized column in the main chamber of the tube because of the very few atoms being exchanged between the two chambers, particularly in the form of the invention in which a packing ring of discharge stopping material intervenes. The device is thus not burdened with dissipating charges due to the action in the tube and we have to consider the result of charges set up by the electrostatic stress between the activated column and the outside conducting body, or which is nearly the same thing, on outside body capable of holding a material charge. The action then is the same problem we have to deal with in a condenser plate, which is that of a displace-

ment of electrons and positive particles along the lines of stress. The length of any such movement being here reduced to such a degree that ionization by collision is very improbable, we thus realize in the direction of the lines of stress much the same insulating effect that we experience in a device such as set forth in my aforesaid copending application. A break down lengthwise thru the gas is resisted by the restrictive effect of a thin body and the packing.

In the form of the invention shown in Figure 3, I provide means to cut up the thin layer of gas into a helix so as to greatly lengthen the break down path through the gas from the main body of the gas in the tube to the plane of the supporting body. The packing in this case also serves as a mechanical support and cushion for the bushing.

In the device shown in Figures 1 and 2 I provide protuberances on the bushing indicated by 12, 12, etc. to position it accurately within the tube. In the latter form these protuberances are eliminated and the packing itself being wound around the bushing serves to locate it accurately in the center of the tube, thus compensating for slight irregularities in commercial glass tube.

In Figure 3 the tube proper is indicated by numeral 20, the electrode end by 21, the electrode proper by 22, the lead in conductor by 23, and the supporting body by 25. A portion of the tube, indicated by 24, is of enlarged diameter and encloses the insulating bushing 26 which is located between the shoulders 27 and 28 of the section 24. The bushing has a helical groove, 31, in which a cord packing of discharge stopping material such as glass wool is placed. This packing should be sufficiently compressible to compensate for the variation in diameter in commercial glass tube.

Having thus described my invention, what I claim is:

1. In a discharge tube, an internal insulator for preventing break down from the inside of said tube to an external body consisting of a dielectric body within said tube in the path of a possible break down discharge, the main portion of said dielectric body being out of contact with the portions of the wall of said tube immediately adjacent thereto leaving a very small space therebetween in which the probability of ionization occurring upon the application of electric stress is so reduced that the said space serves as additional insulation, the length of a possible break down passage from the main chamber in said tube to any possible break down point on the wall of said tube near said dielectric body being of such length that the probability of such break down is reduced to a very low value.

2. In a discharge tube, an internal insulator for preventing break down from the inside of said tube to an external body consist-

- ing of a dielectric body within said tube in the path of a possible break down discharge, the main portion of said dielectric body being out of contact with the portions of the wall of said tube immediately adjacent thereto leaving a very small space therebetween in which the probability of ionization occurring upon the application of electric stress is so reduced that the said space serves as additional insulation, and means to prevent a break down discharge from the main chamber in said tube thru said space to a possible break down point on the wall of said tube near said dielectric body.
3. In a discharge tube, an internal insulator for preventing break down from the inside of said tube to an external body consisting of a dielectric body within said tube in the path of a possible break down discharge, the main portion of said dielectric body being out of contact with the portions of the wall of said tube immediately adjacent thereto leaving a very small space therebetween in which the probability of ionization occurring upon the application of electric stress is so reduced that said space serves as additional insulation, and discharge stopping means between said space and the main chamber of said discharge tube.
4. In a discharge tube, an internal insulator for preventing break down from the inside of said tube to an external body consisting of a dielectric body within said tube in the path of a possible break down discharge, the main portion of said dielectric body being out of contact with the portions of the wall of said tube immediately adjacent thereto leaving a very small space therebetween in which the probability of ionization occurring upon the application of electric stress is so reduced that said space serves as additional insulation, and a packing body of discharge stopping material interposed between said space and the main chamber of said tube.
5. In a discharge tube, an internal insulator for preventing break down from the inside of said tube to an external body consisting of a dielectric body within said tube in the path of a possible break down discharge, the main portion of said dielectric body being out of contact with the portions of the wall of said tube immediately adjacent thereto leaving a very small space therebetween in which the probability of ionization occurring upon the application of electric stress is so reduced that said space serves as additional insulation, and a packing of discharge stopping material between said dielectric body and the adjacent wall of said tube in the path of a possible break down discharge between said body and said wall thru said space.
6. In a discharge tube, an internal insulator for preventing break down from the in-
- side of said tube to an external body consisting of a dielectric body within said tube in the path of a possible break down discharge, the main portion of said dielectric body being out of contact with the portions of the wall of said tube immediately adjacent thereto leaving a very small space therebetween in which the probability of ionization occurring upon the application of electric stress is so reduced that said space serves as additional insulation, and a helical packing of discharge stopping material between said body and the adjacent wall of said tube disposed to cut said space into a helix whereby to greatly increase the length of a possible discharge thru said space from the main chamber in said tube by causing the same to take a helical course.
7. In a discharge tube, an internal insulator for preventing break down from the inside of said tube to an external body consisting of a dielectric bushing positioned within said tube in the path of a possible break down discharge having an outside diameter slightly less than the inside diameter of the surrounding tube wall, a helical groove in said bushing and a helical packing of discharge stopping material in said groove bearing against said wall and locating said bushing within the said tube.
8. In a gaseous conduction tube mounting wherein the tube is mounted upon a support and extends thru a conductive portion thereof, means for preventing break down discharge from the interior of the tube to said portion consisting of a dielectric bushing within said tube, and extending on opposite sides of said portion.
9. In a gaseous conduction tube mounting wherein the tube is mounted upon a support and extends thru a conductive portion thereof, means for preventing break down discharge from the interior of the tube to said portion consisting of a dielectric bushing within said tube the main portion of which is out of contact with the wall of said tube immediately adjacent thereto leaving a very small space therebetween.
10. In a gaseous conduction tube mounting wherein the tube is mounted upon a support and extends thru a conductive portion thereof, means for preventing break down discharge from the interior of the tube to said portion consisting of a dielectric bushing within said tube extending a substantial distance along the wall of the tube on both sides of said portion, the main portion of said bushing being out of contact with the adjacent wall of the tube leaving a very small space therebetween in which the probability of ionization occurring upon the application of electric stress is so reduced that said space serves as additional insulation.
11. In a gaseous conduction tube mounting wherein the tube is mounted upon a sup-

- port and extends thru a conductive portion thereof, means for preventing break down discharge from the interior of the tube to said portion consisting of a dielectric bushing within said tube extending a substantial distance along the wall of the tube on both sides of said portion, the main portion of said bushing being out of contact with the adjacent wall of the tube leaving a very small space therebetween in which the probability of ionization occurring upon the application of electric stress is so reduced that said space serves as additional insulation, and means to prevent break down discharge thru said space from the main chamber of said tube.
12. In a gaseous conduction tube mounting wherein the tube is mounted upon a support and extends thru a conductive portion thereof, means for preventing break down discharge from the interior of the tube to said portion consisting of a dielectric bushing within said tube extending a substantial distance along the wall of the tube on both sides of said portion, the main portion of said bushing being out of contact with the adjacent wall of the tube leaving a very small space therebetween in which the probability of ionization occurring upon the application of electric stress is so reduced that said space serves as additional insulation, and packing means of discharge stopping material separating said space from the main chamber of said tube.
13. In a gaseous conduction tube mounting wherein the tube is mounted upon a support and extends thru a conductive portion thereof, means for preventing break down discharge from the interior of the tube to said portion consisting of a dielectric bushing within said tube extending a substantial distance along the wall of the tube on both sides of said portion, the main portion of said bushing being out of contact with the adjacent wall of the tube leaving a very small space therebetween in which the probability of ionization occurring upon the application of electric stress is so reduced that said space serves as additional insulation, and a helical packing of discharge stopping material between said bushing and the adjacent wall of said tube cutting said space into a helix to increase to a considerable extent the length of a possible break down discharge from the main chamber of said tube thru said space.
14. In a gaseous conduction tube mounting wherein the tube is mounted upon a support and extends thru a conductive portion thereof, means for preventing break down discharge from the interior of the tube to said portion consisting of a dielectric bushing within said tube extending a substantial distance along the wall of the tube on both sides of said portion, the main portion of said bushing being out of contact with the adjacent wall of said tube leaving a very small

space therebetween in which the probability of ionization occurring upon the application of electric stress is so reduced that said space serves as additional insulation, and a plurality of annular barriers of discharge stopping material in the path of any possible break down discharge from the main chamber of said tube thru said space.

Signed at Chicago, Illinois, this 19th day of March, 1931. 70 75

FRED HOTCHNER. 20
